UNITED STATES PATENT OFFICE.

ALBERT F. FIFIELD, OF NEWARK, NEW JERSEY, ASSIGNOR TO THE SINGER MANUFACTURING COMPANY, A CORPORATION OF NEW JERSEY.

THREAD-SEVERING MECHANISM FOR SEWING-MACHINES.

1,346,814.

Specification of Letters Patent. Patented July 20, 1920.

Application filed September 23, 1916. Serial No. 121,705.

To all whom it may concern:

Be it known that I, ALBERT F. FIFIELD, a citizen of the United States, residing at Newark, in the county of Essex and State of New Jersey, have invented certain new and useful Improvements in Thread-Severing Mechanisms for Sewing-Machines, of which the following is a specification, reference being had therein to the accompanying drawings.

This invention relates to improvements in sewing machines, particularly of the type embodying an automatic mechanism acting to stop the machine at the completion of a predetermined number of stitches. Machines of this type are commonly used for sewing on buttons, stitching buttonholes, bar-tacking, &c., and in order that the work may present a finished appearance when it is removed from the machine it is desirable to provide mechanism for severing the stitching thread or threads close to the under surface of the work at the completion of a stitching operation.

To prevent unthreading of the needle and insure the certain concatenation of the stitching thread or threads when the machine is restarted, it is customary to provide an implement for receiving and detaining the last needle-loop shed from the loop-taker so that the take-up, in completing its last up-stroke, may pull additional thread from the supply and thus provide a length of needle-thread sufficient for the beginning of the next stitching operation. It is also customary to provide a thread-gripping device which acts to grip the free end of the needle-thread drawn down by the loop-taker when the machine is restarted, in order that the beginning end of the needle-thread may be located at the under side of the work. It is further customary in lock-stitch machines of the above type to provide an implement for pulling off a length of bobbin-thread prior to the thread-severing operation in order that the cut end of the thread issuing from the bobbin may be long enough to be caught and drawn up to the work by the first needle-loop cast about the bobbin. The path of movement and time of operation of each of the various implements must be accurately controlled and for this reason it has heretofore been the practice to mount and operate these implements independently of

each other, thus necessitating a more or less 55 complicated mechanism embodying a relatively large number of parts.

One of the primary objects of the present invention is to provide a simplified thread-severing mechanism in which a single implement is adapted to detain the last needle-loop below the throat-plate for the action of the thread severing implement and subsequently 60 nip the beginning end of the needle-thread.

Another object of the invention is to provide a lock-stitch machine with a simplified thread-severing mechanism in which a single implement is adapted to detain the last needle-loop, to pull off bobbin-thread, 70 and to nip the free end of the needle-thread when the machine is restarted.

A further object of the invention is to provide a machine with thread-cutting mechanism including a single implement adapted 75 to perform any two of the three above mentioned functions.

Further objects of the invention will appear from the following description and 80 claims.

The present improvement, in its preferred embodiment, is shown applied to a lock-stitch machine of the well known type disclosed in the United States patent to J. J. Sullivan, No. 777,564, of December 13, 1904, 85 to which reference may be made for details of the present machine not specifically referred to herein and in which the pattern-cam and stop-motion lever are adapted to impart the usual plural-stage longitudinal 90 movement to an actuator-bar extending lengthwise of and beneath the bed-plate of the machine. In the present instance an implement or finger performing the functions of detaining and spreading the needle-loop, pulling off bobbin-thread, and subsequently nipping the free end of the needle-thread, is pivotally mounted on the under side of the throat-plate adjacent the needle-aperture for movement in a plane at right 95 angles to the needle-path. This finger is, at certain times, moved forward and backward across the needle-path by a bellcrank-lever fulcrumed beneath the bed-plate and actuated by a slotted cam-plate secured to the 100 actuator-bar above referred to.

The thread severing device comprises a stationary ledger-blade, secured to the under

side of the throat-plate adjacent the needle-aperture, and a movable blade which is pivotally mounted on the throat-plate in co-operative relation with the ledger-blade, 5 and which has a lost-motion connection with the actuator-bar. Just prior to the stopping of the machine the actuator-bar receives the first stage of its movement to advance the finger to loop-detaining position 10 and upon the stopping of the machine the overthrow of the main-shaft gives the well known second-stage movement to the actuator-bar which in the present instance causes the cutting blade to quickly enter the 15 spread needle-thread loop and sever one limb thereof together with the bobbin-thread. When the machine is restarted the detaining finger is returned toward its initial position and during its movement passes 20 backwardly across the needle-aperture in the throat-plate, carrying the free end of the needle-thread loop and nipping the same against a spring-plate mounted upon the under side of the throat plate. After the 25 first few stitches have been formed a further movement of the detaining finger releases the needle-thread.

In the drawings, Figure 1 is a rear side elevation, partly in section, of a sewing machine embodying the present improvements. 30 Fig. 2 is a bottom plan view of the machine. Fig. 3 is a rear end elevation. Fig. 4 is a bottom plan view of the throat-plate of the machine together with the operative parts mounted thereon. Fig. 5 is a section along the line 5—5; Fig. 4, the parts being upside down. Fig. 6 is a similar section along the line 6—6; Fig. 4. Figs. 7 to 12 inclusive are perspective views showing the 35 relative positions of the operative parts beneath the throat-plate during successive stages of a thread detaining, severing and nipping operation.

The frame of the machine is formed with 40 the bed-plate 1 from which rises the standard 2 supporting the overhanging bracket-arm 2* in which is journaled the main-shaft 3 carrying the tight and loose pulleys 4 and 5. Connected to the main-shaft 45 through the link 6 is the needle-bar 7 carrying an eye-pointed needle 8 co-operating with a loop-taking implement which, in the present instance, is illustrated in the form of a shuttle 9 carrying a bobbin 10 about 50 which the needle-thread loops are cast during the production of a series of lock-stitches. The shuttle 9 is oscillated in a manner well known through the usual connections with the main-shaft 3, comprising 55 the crank 11, pitman 12, rock-lever 13 and shuttle driving shaft 14. The main-shaft 3 also carries the usual take-up actuating cam 14* which vibrates the take-up lever 14* in an old and well known manner. The 60 machine is equipped with a common form of 65

work-holder 15 to which lateral jogging movements are imparted by the usual connections with the pattern-cam 16 which is mounted on a cross shaft 17 carrying a worm-wheel 18 meshing with the worm 19 70 on the main-shaft 3, all of which structure is fully disclosed in the Sullivan patent above referred to.

The present machine is also provided with the well known stop-motion mechanism embodying substantially the constructive features illustrated in the aforesaid Sullivan patent. At the rearward side of the standard 2 is a bracket 20 which is formed in its lower end with a socket in 75 which is journaled the cylindrical plug 21 whose outer end is slotted to receive the usual vibratory stop-lever 22 which is pivotally connected to the plug 21 by a pin 23, and which carries at its upper end the usual 80 spring-pressed plunger rod 24 whose wedge-shaped upper end 25 is adapted for engagement with the well known stopping cam 26, into operative relation with which it is normally pressed by suitable means such as the 85 spring 27. The stop-lever 22 is yieldingly confined against one of the spaced flanges 28 of the bracket 20 by means of the transverse plunger-rod 29 mounted in the socketed bearing boss 30 in which is confined the 90 buffer-spring 31. The stop-lever carries the 95 usual belt-shipper 32.

The rearward face of the stop-lever 22 is formed with a groove 33 which is entered by the hooked outer extremity of the usual 100 latch-lever 34 pivoted upon the fulcrum-screw 35 and having a forwardly extending arm 36 whose extremity is normally forced by a coiled spring 37 into the path of circular movement of the tripping lug 38 secured 105 within the inner recessed face of the cam-wheel 16. In practice this tripping lug is so arranged that the latch-lever 34 is tripped to release the stop-lever 22 as the needle completes its descent for the final tying stitch succeeding each group of fastening stitches. The usual starting lever 39 is provided for tilting the stop-lever to disengage the plunger from the stopping cam and shift the belt onto the tight pulley 4. 110

The single implement which serves to detain and spread the last needle-loop, to pull off the bobbin-thread, and to subsequently nip the beginning end of the needle-thread, 115 is in the form of a finger 40 and is pivotally mounted between its ends on the under side of the throat-plate 41 by means of the vertically disposed screw-pin 42. The finger 40 is formed with a reduced shank 43, Fig. 6, terminating in a thickened head 44 which is 120 extended laterally in one direction to form two beaks 45 and 46 defining between them a loop receiving throat 47. The head 44 is provided at a point opposite the throat 47 with a V-shaped needle-thread receiving 125 130

notch 48. The side of the head 44 adjacent the throat-plate is flattened to form a thread-nipping surface 49, Figs. 5 and 6, which is spaced from a reduced portion of the under surface of the throat-plate and is adapted to coöperate with a complementary thread-nipping surface 50 disposed at the under side of the throat-plate and preferably in a substantially horizontal plane. In practice, this nipping surface may conveniently be provided at the free end of the flat spring 51 which is fitted in a recess 52 in the under side of the throat-plate and held in position by the screw 53. In the present instance, the free end of the spring 51 may yield somewhat when the needle-thread is caught between the nipping surfaces 49 and 50.

Mounted on the finger 40, at the extremity opposite the head 44, is a roller-stud 54 which is embraced by the forked extremity 55 of one arm 56 of a bellcrank-lever culcrumed at 57 to the fixed plate 58 secured to the under side of the bed-plate 1. The other arm 59 of the bellcrank-lever is slotted at 60 and the stud-pin 61, adjustably secured in the slot 60 by a nut 62, enters the cam-slot 63 in the cam-plate 64 screwed to the well known actuator-bar 65 which extends longitudinally of the bed-plate in machines of this type.

In the present instance means, preferably shear-cutters comprising movable and stationary blades, are provided for severing the stitching threads close to the needle-hole at the under side of the throat-plate at the end of a stitching operation. The movable blade 66 is in the form of a lever loosely fulcrumed at one end on the stud-screw 67 and having adjacent its opposite end a cutting edge 68 which is adapted to coöperate with the complementary cutting edge 69 of the ledger-blade 70 secured in a recess in the under side of the throat-plate 41 adjacent the needle-hole 71 by a screw 72. When the cutting blade is in advanced position the contacting faces of the ledger and cutting blades are yieldingly held in engagement by the arched spring-plate 73 which is seated over the rearward extremity of the cutting blade 66 and held in position by the screw 67. The spring-plate 73 is formed with a pair of bent lips 74 which embrace opposite edges of the cutting blade and prevent relative turning movements between said blade and spring-plate about the stud-screw 67.

To facilitate the entry of the cutting blade into the detained needle-loop, it is desirable to provide a certain amount of clearance between the cutting blade and the throat-plate when the former is in retracted position. To accomplish this result an elongated wedge-plate 75 having one extremity tapered down to a thin edge 76 is secured to the under surface of the throat-plate by a

screw 77 and is so positioned that as the cutting blade is moved back from cutting position it will strike the inclined surface 78 of the wedge-plate 75, Figs. 5 and 6, and be forced away from the throat-plate a distance equal to the thickness of the wedge-plate 75.

The cutting blade is actuated through a sidebar 79 having a lost motion connection with the actuator-bar 65. The slide-bar 79 is fitted within the guide-way 80 formed in a guide-block 81 secured to the throat-plate by screws 82. One extremity of the slide-bar 79 carries a pin 83 which is loosely fitted within the concentric apertures 84 and 85 formed, respectively, in the spring-plate 73 and the cutting blade 66 near the fulcrum-screw 67. A slight amount of play is provided between the opposite side-walls of the slide-bar 79 and guide-way 80, as shown in Fig. 4, to permit limited side-wise movement of the bar 79 caused by the small movement of the pin 83 about the screw 67 as a center. The portion of the slide-bar 79 within the guide-block 81 is formed with a rectangular slot 86 within which projects an abutment 87 sustained by the throat-plate 41. A expansion spring 88 housed within the slot between the abutment 87 and the end wall 89 serves to yieldingly return the cutting blade to initial position. The abutment-pin 90 sustained by the slide-bar 79 is adapted to be struck at a predetermined time by the tappet 91 secured by screw 92 to the lateral extension piece 93 which in turn is screwed to the actuator-bar 65. When the parts are in initial position, Fig. 2, the tappet 91 is spaced from the abutment-pin 90 and for this reason the first stage of the longitudinal movement of the actuator-bar does not transmit motion to the cutter-blade.

The actuator-bar 65 at its left hand extremity, Fig. 2, carries a block 94 recessed at 95, to receive the lower extremity of the usual vibratory lever 96 fulcrumed at 97 to a bracket 98 sustained by the bed-plate and carrying at its upper extremity a pin 99 which fits into the cam-groove 100 common to machines of this type. The block 94 carries a stud-pin 101 which is embraced by the forked extremity of one arm of a bellcrank-lever 102 pivoted at 103 to the under side of the bed-plate. The other arm 104 of the bellcrank-lever is socketed to receive the plunger-pin 105 which is urged outwardly by the spring 106 in a manner well known. When the stop-lever 22 is tripped into action the plunger-pin 105 snaps into the slot 107 in the lower extremity of the stop-lever 22 and the overthrow of the stop-lever in opposition to the buffer-spring 31 acts to rock the bellcrank-lever 102 and impart a sudden endwise movement to the actuator-bar 65.

During the operation of the machine, while the pattern-cam 16 is imparting lateral jogging movements to the work-holder to position the individual stitches of the group being formed, the detaining finger 40 is in retracted position, as shown in Fig. 2, and the cutting blade is in initial position as shown in Fig. 4. As the needle descends preparatory to throwing out the last loop prior to the release of the stop-lever 22, the irregular portion 108 of the cam-slot 100 acts upon the pin 99 to shift the lever 96 and actuator-bar 65 to the left, Fig. 2, thus causing the finger 40 to swing about its pivot and advance the head 44 toward the needle-hole 71. As the shuttle seizes the loop thrown out by the rising needle and is drawing out such loop, the head 44 is moved across the needle-path, thereby projecting the beak 45 between the shuttle-thread *t* and the limb *n* of the needle-loop. At the same time the loop-dividing beak or point 46 is projected into the needle-loop, as shown in Fig. 7.

By the time the needle reaches its highest position the shuttle has turned to cast-off position, Fig. 8, and the finger 40 continuing its advance reflects the shuttle-thread *t*, thereby pulling a given length from the bobbin 10, and holds the limb *n* of the needle-loop in the throat 47. As the needle-loop is cast about the shuttle the usual take-up 14^b comes into action and draws up the limb *s* thus reducing the size of the needle-loop, and tightening said loop about the head of the loop detaining finger 40. As the detaining finger 40 prevents the complete drawing up of the last needle-loop by the take-up, the latter in completing its up-stroke will necessarily pull off an abnormal length of thread from the supply. By virtue of the abnormal pull off action of the take-up at this time enough slack thread is provided for the beginning of the next stitching operation and unthreading of the needle by the take-up is avoided. After the take-up 14^b has completed its up-stroke the parts are arranged as shown in Fig. 9, wherein the bobbin-thread *t* and the limb *n* of the needle-loop are positioned in the path of movement of the cutting blade 66. The limb *s* of the needle-loop leads to the needle and is held above the path of movement of the cutting blade 66 by the surface 49. It is to be remembered that the cutting blade is at this time held away from the throat-plate by the wedge-plate 75 and plenty of clearance is provided for the positioning of the limb *s* above the path of movement of the cutter-blade 66, by the raised surface 49 of the detaining finger 40. The thickened head 44 of the finger 40 thus serves to detain and hold open the last loop of needle-thread so that the advancing cutter-blade 66 may enter the spread needle-loop and sever

the limb *n* thereof together with the bobbin-thread *t*, against the edge 69 of the ledger-blade, as shown in Fig. 10.

The actuator-bar 65 during the second stage of its movement caused by the overthrow of the stop-lever, carries the tappet 91 into engagement with the abutment pin 90 to impart the cutting impulse to the blade 66. At this time the pin 61 is given a slight movement toward the actuator-bar 65 by the inclined extremity 63^x of the cam-slot 63, (Figs. 9 and 12), and the bellcrank lever 56, 59 which carries the pin 61, is caused to move the detaining finger 40 toward the needle-hole a distance sufficient to compensate for the deflection of the limb *n* of the needle-loop and the bobbin-thread *t* by the cutter blade as it crosses the needle-hole and carries the thread to the ledger-blade, as will be clear from an inspection of Figs. 9 and 10.

As the needle descends at the beginning of the next stitching operation there is a sufficient length of thread projecting through the eye thereof to permit the formation of the first loop which is caught by the bobbin as shown in Fig. 11. At the same time an active portion of the cam-slot 100 serves to shift the actuator-bar 65 and impart a return movement to the detaining finger 40. As the V-shaped notch 48 is moved across the needle-path it engages the needle-thread immediately after the free end thereof has been drawn down below the work by the shuttle and carries it backwardly across the active surface 50 of the stationary nipper spring 51 against which it is held by the nipping surface 49 of the detaining finger. The thread is actually nipped just before the needle completes its first up-stroke.

During the second reciprocation of the needle-bar the first needle-loop is cast about the bobbin and this loop catches the length of thread issuing from the bobbin and draws it up to the work. Since this length of bobbin-thread includes the amount pulled from the bobbin prior to the preceding thread-cutting operation, it will be clear that there will be a short end of bobbin-thread projecting from the first stitch. The beginning end of the needle-thread is held during the formation of the first two complete stitches, after which the actuator-bar 65 receives a further impulse to the right, Fig. 2, and returns the detaining finger 40 to initial position thus releasing the end of the needle-thread. In practice, the beginning ends of the needle and bobbin-threads are covered by the stitches of the group being formed.

Having thus set forth the invention, what I claim herein is:—

1. In a sewing machine, in combination, stitch-forming mechanism including a reciprocating needle a bobbin and a take-up, a

needle-loop detaining implement, means whereby said implement is caused to pull thread from the bobbin, and means for severing the needle- and bobbin-threads.

5. 2. In a sewing machine, in combination, stitch-forming mechanism including a reciprocating needle a bobbin and a take-up, a needle-loop detaining implement, means whereby said implement is caused to pull thread from the bobbin, means for severing the needle- and bobbin-threads, and means whereby said implement is subsequently caused to nip the needle-thread.

10. 3. In a sewing machine, the combination with stitch-forming mechanism including a reciprocating needle a shuttle and a take-up, of an implement adapted to enter and detain the last needle-loop acted upon by the take-up, said implement being movable across the 20 path of the shuttle-thread and serving as a pull-off for the shuttle-thread, and means for severing the needle- and shuttle-threads.

4. In a sewing machine, in combination, stitch-forming mechanism including a reciprocating needle and a shuttle, a finger movable in a plane transversely of the needle-path to engage and pull off shuttle-thread and to enter and detain the last needle-thread loop cast about the shuttle, a thread-cutter and means for moving the latter into operative engagement with the bobbin-thread and one limb of the detained needle-thread loop.

5. In a sewing machine, in combination, a reciprocating needle and complemental loop-taking means, a throat-plate, a finger movable in one direction to enter and detain the last needle-thread loop formed during the production of a series of stitches, and a 40 thread severing implement movable across the lead of that limb only of the detained needle-loop which leads to the last stitch, said finger being movable in the reverse direction to nip the needle-thread at the under 45 side of the throat-plate at the beginning of the next stitching operation.

6. In a sewing machine, in combination, stitch-forming mechanism including a reciprocating needle and a bobbin, a work-plate 50 having a needle-hole, a finger movable across the path of the bobbin-thread to deflect the latter, said finger also serving to enter and detain the last needle-loop cast about the bobbin, and a thread severing implement 55 mounted adjacent the needle-hole and adapted to sever the bobbin-thread and that limb only of the detained needle-loop which leads to the last stitch.

7. In a sewing machine, in combination, 60 stitch-forming mechanism including a reciprocating needle and complemental loop-taking means, a throat-plate, a thread-nipping surface disposed at the under side of the throat-plate, a needle loop-detaining implement, a complementary thread-nip-

ping surface formed on said implement, means for moving said implement to a position to engage and detain the last needle-loop at the completion of a series of stitches, a cutter moving automatically to sever the 70 detained needle-loop, and means whereby said thread-nipping surfaces are caused to detain the end of the needle-thread at the beginning of the next stitching operation.

8. In a sewing machine, in combination, 75 stitch-forming mechanism including a reciprocating needle and a bobbin, thread severing means, coöperating thread nipping elements adapted to nip the free end of the needle-thread at the beginning of a stitching 80 operation, and means for moving one of said elements sufficiently across the path of the bobbin-thread at the end of a stitching operation to pull off enough bobbin-thread to insure that the free end of the bobbin-thread will be caught up at the beginning 85 of the next stitching operation.

9. In a sewing machine, in combination, stitch-forming mechanism including a reciprocating needle and a bobbin, thread 90 severing means, coöperating thread-nipping elements adapted to nip the free end of the needle-thread at the beginning of a stitching operation, and means for moving one of said elements across the path of the bobbin-thread at the end of a stitching operation to pull off enough bobbin-thread to permit the starting of a new stitching operation, said last mentioned one of said elements operating further to detain for the 95 action of the thread-cutter the last needle-loop cast about the bobbin.

10. In a sewing machine, the combination with stitch-forming mechanism including a reciprocating needle and lower thread 105 loop-taking means, of a thread-severing implement, and a thread positioning implement movable across the path of the needle and lower-threads and having a first projection adapted to pass between the lower-thread and the last loop of needle-thread caught by the shuttle, and a second projection adapted to enter the needle-thread loop.

11. In a sewing machine, the combination with stitch-forming mechanism including a reciprocating needle and lower-thread loop-taking means, of a thread-severing implement, and a thread-engaging implement movable across the path of the needle- and lower-threads, and having a first projection 115 adapted to pass between the lower-thread and the last loop of needle-thread caught by the shuttle, and a second projection adapted to enter and position the needle-thread loop for the thread-severing operation, said thread-engaging implement being further provided with a notch adapted to receive and deflect the loose end of the needle-thread at the beginning of a stitching operation.

12. In a sewing machine, in combination, a stitch-forming mechanism including a needle and complementary loop-taking means, a fixed part having a thread-nipping surface, a needle-loop detaining implement having a complementary thread-nipping surface, a thread-severing knife mounted for movement relatively to said implement, and means for moving said implement at the end of a stitching operation to enter and detain the last loop of needle-thread for the action of the thread-severing device and for subsequently moving said implement at the beginning of a new stitching operation to nip the beginning end of the needle-thread against said fixed part.
13. In a sewing machine, in combination, a stitch-forming mechanism including a needle and shuttle, a thread-severing device, a part having a thread-nipping surface, a thread-positioning implement having a complementary thread-nipping surface, and means for moving said implement across the path of the shuttle-thread at the end of a stitching operation to pull off shuttle-thread, and for subsequently moving said implement at the beginning of a stitching operation to nip the beginning end of the needle-thread.
14. In a sewing machine, in combination, a stitch-forming mechanism including a needle and shuttle, a thread-severing device, a part having a thread-nipping surface, a needle-loop detaining implement having a complementary thread-nipping surface, and means for moving said implement across the path of the needle and shuttle-threads at the end of a stitching operation to pull off the shuttle-thread and to detain the last needle-thread loop for the action of a thread-severing device and for subsequently moving said implement at the beginning of a new stitching operation to nip the beginning end of the needle-thread.
15. In a sewing machine, in combination, a frame, stitch-forming mechanism including a reciprocating needle and a take-up, a stop-mechanism, a needle-loop detaining implement, a thread-severing implement, an actuator controlled by said stop-mechanism, said implements being carried by the frame independently of said actuator and an operative connection between said actuator and said implements whereby they are differentially actuated.
16. In a sewing machine, in combination, a stitch-forming mechanism including a reciprocating needle, an automatic stop mechanism, a thread-positioner, a thread-cutter, an actuator controlled by said stop mechanism, a connection between said actuator and said thread-positioner, and a lost-motion connection between said actuator and said thread-cutter.
17. In a sewing machine, in combination,

stitch-forming mechanism including a reciprocating needle, a throat-plate carrying a ledger-blade at its under side, a cutter-blade mounted for movement in a plane parallel with said ledger-blade and also in a direction transverse to said plane, means for imparting cutting and return movements to said cutter-blade and means for moving said cutter-blade transversely of the plane of said first mentioned movements.

18. In a sewing machine, the combination with a frame and stitch-forming mechanism incorporated therein and including a reciprocating needle, a shuttle and a take-up, of an implement pivoted at a fixed point relatively to said frame and adapted to enter and detain the last needle-loop acted upon by the take-up, said implement being movable across the path of the shuttle-thread and serving as a pull-off for the shuttle-thread, and means for severing the needle- and shuttle-threads.

19. In a sewing machine, the combination with a frame including a throat-plate, a thread-nipping surface sustained at the under side of the throat-plate, and stitch-forming mechanism incorporated in said frame and including a reciprocating needle, a shuttle and a take-up, of an implement pivoted to said throat-plate at a fixed point and adapted to move in one direction to enter and detain the last needle-loop of a series for the action of the thread-cutter and to pull off shuttle thread, said implement being movable in the reverse direction at the beginning of a stitching operation to nip the needle-thread against said thread-nipping surface.

20. Thread-cutting and nipping mechanism for sewing machines comprising a thread-cutter and means including a single movable thread-engaging implement operating to pull off bobbin-thread, to detain and spread the last needle-loop of a series for the action of the thread-cutter and to nip the beginning end of the needle-thread at the start of a new stitching operation.

21. In a sewing machine, the combination with a frame including a throat-plate having a needle-aperture, and stitch-forming mechanism incorporated in said frame and including a reciprocating needle, a shuttle and a take-up, of a thread-cutter including a movable blade and a fixed blade, the latter being carried by the throat-plate adjacent the needle-aperture, and a needle-loop detainer and spreader about which the needle-thread loop which has been passed around the shuttle is tightened by the take-up, said needle-loop detainer and spreader being movable across the lead of the bobbin-thread and operating to pull off bobbin-thread and position said bobbin-thread and one limb only of the needle-loop in the path of said movable blade.

22. In a sewing machine, the combination with a frame including a throat-plate and stitch-forming mechanism incorporated in said frame and including a reciprocating needle, a shuttle, and a take-up, of a thread-cutter including a movable blade sustained beneath the throat-plate, and a needle-loop detaining and spreading finger moving in a plane substantially parallel to the throat-plate and having a thickened extremity adapted to position the two limbs of the last needle-loop mainly at opposite sides of the plane of movement of the cutter. 5
- 10 23. In a sewing machine, the combination with a frame including a throat-plate and stitch-forming mechanism incorporated in said frame and including a reciprocating needle, a shuttle, and a take-up, of a thread-cutter including a movable blade sustained beneath the throat-plate, and a needle-loop detaining and spreading finger moving in a plane substantially parallel to the throat- 15

plate and having a thickened extremity adapted to position the two limbs of the last needle-loop mainly at opposite sides of the 25 plane of movement of the cutter, said finger being further formed with a reduced shank-portion adapted to engage and pull off sufficient bobbin-thread to permit the starting of a new stitching operation. 30

24. In a sewing machine, in combination, a reciprocating needle, a loop-taker operating to seize and distend needle-loops for passage about a lower thread mass, a take-up, a needle-loop detainer and spreader having a loop-dividing point, automatic means for moving said point into the last needle-loop during the early part of the distension of said loop by said loop-taker, and means for severing the detained needle-loop. 35

40 In testimony whereof, I have signed my name to this specification.

ALBERT F. FIFIELD.
